Primary Examiner — Darlington Ly(57) **CLAIM**

The ornamental design for a beach bicycle frame as shown and described.

DESCRIPTION

FIG. 1 is a top, front and right side perspective view of a beach bicycle frame showing my new design;
FIG. 2 is a bottom, rear and left side perspective view thereof;
FIG. 3 is a top, rear and right side perspective view thereof;
FIG. 4 is a front elevational view thereof;
FIG. 5 is a rear elevational view thereof;
FIG. 6 is a left side elevation view thereof;
FIG. 7 is a right side elevation view thereof;
FIG. 8 is a top plan view thereof;
FIG. 9 is a bottom plan view thereof;
FIG. 10 is an enlarged view of portion 10 in FIG. 1; and,
FIG. 11 is an enlarged view of portion 11 in FIG. 1.
The broken lines in the drawings illustrate portions of the beach bicycle frame which form no part of the claimed design.

1 Claim, 11 Drawing Sheets(56)
